UNITED STATES PATENT OFFICE

CARROLL A. HOCHWALT AND JOHN B. WALIUSZIS, OF DAYTON, OHIO, ASSIGNEES TO
MORTON SALT COMPANY, OF CHICAGO, ILLINOIS, A CORPORATION OF ILLINOIS

PREPARATION OF BROMATES

No Drawing.

Application filed March 19, 1932. Serial No. 600,065.

This invention relates to the production of pure bromates, such as potassium bromate, and to a method of purifying bromates.

One of the principal objects of this invention is to produce a pure and colorless bromate, such as potassium bromate, from an impure bromate such as is produced by electrolytic methods and using a chromate as a depolarizer.

Another object of the invention is to provide a simple and practical method for producing such pure and colorless bromate.

Another object of this invention is to produce a bromate which is free from chromates, by the use of an adsorbing material which has special affinity for the chromate, such as metallic zinc or zinc dust.

Other objects and advantages of the invention will be apparent from the following description and appended claims.

One of the methods of commercial production of bromates is by electrolysis of bromide solutions. It is generally recognized that in order to produce a commercially practical yield of bromate, the use of a depolarizer is necessary. A material found highly effective and practical as a depolarizer is a chromate, such as potassium chromate or potassium dichromate. It is found, however, that when a chromate is used in the ordinary manner as a depolarizer, part of the chromate is carried over into the solution of bromate, and a yellow discoloration is thereby produced in the finished crystals of bromate, such as potassium bromate. It has been found practically impossible to separate this chromate from the bromate by fractional crystallization or by washing or reprecipitation as sufficient chromate still remains to give an objectionable yellow color to the bromate crystals. Ordinary adsorbing agents also have been found commercially ineffective.

We have now discovered that such bromates, containing chromate as an impurity, can be effectively decolorized by treatment with a material found to have a peculiar affinity for the chromate impurity when used as an adsorbing agent therefor. The material found most effective for this purpose is me-

tallic zinc, which is conveniently and effectively used in the form of zinc dust.

As an example of the carrying out of this invention the following procedure is described.

Any suitable type of cell construction may be utilized for the electrolysis of bromides, such as potassium bromide, to produce a bromate such as potassium bromate. Various factors are to be taken into account and calculated in the construction of the particular cell used, so as to obtain a current density which is practical for efficient electrolysis. For example, an anode current density of 3 to 9 amperes per square decimeter has been found to produce good yields of bromates. Carbon electrodes are found satisfactory. The particular cell described is given merely as an example, as it will be readily understood that such a cell may be constructed to satisfy widely varying conditions. The essential factors in any cell are so calculated and adjusted as to produce the required conditions for electrolytic production of bromates.

A cell designed as follows was found to produce good results: The cell used has a capacity of 100 gallons. The weight of 100 gallons of 25 per cent potassium bromide solution is approximately 1025 pounds, the weight of potassium bromide being approximately 256 pounds. The current required for conversion of this amount of bromide to bromate is calculated as 157,049 ampere hours. Assuming a current of 800 amperes, the time required is 196.3 hours; the theoretical production is 359.2 pounds of potassium bromate. Assuming a cell efficiency of 66 2/3 percent, the bromate produced per 100 gallon cell is 239.2 pounds.

The cell used was a rectangular iron tank lined with tile. Any desired non-corrosive or non-contaminating material may be used for construction of the tank. For example, glass lined tanks are satisfactory. The inside dimensions of this cell are: 29 inches by 22 inches by 42 inches in height. The liquor level when the cell is filled with 100 gallons of liquor has a height of 3.017 feet. An electrode immersion of 27 inches was required in

order to give a current density of 7 amperes per square decimeter. The electrodes are of graphite 2 inches square and 33 inches long. The 12 electrodes used displace about 1½ inches of liquor. The exact displacement is determined with each set of electrodes used. These dimensions allow a 10½ inch free space on the bottom of the tank, the liquor level being about 4.5 inches below the top of the tank.

The potassium bromide solution (100 gallons of 25% potassium bromide solution) containing 0.5 gram of potassium chromate per liter as a depolarizer, is electrolyzed in the described cell. The electrolysis is continued for the calculated period of time required for complete conversion of potassium bromide to potassium bromate. The solution is then pumped into an adjoining jacket tank. This tank may be constructed or lined with any desired non-corrosive material, for example the tank may be glass lined or enamel lined. In this tank the solution is diluted with a sufficient volume of water to completely dissolve all potassium bromate crystals. The diluted solution is preferably boiled until complete solution has taken place. The solution is then filtered to remove any foreign matter, such as graphite particles from the electrodes. The filtered solution is evaporated until potassium bromate crystals begin to form. The solution is then cooled and the liquor decanted off from the crystals. This liquor may be used again as make-up liquor for another electrolysis, after addition of the necessary potassium bromide and potassium chromate. When the mother liquor is used for make-up liquor, it is found that a number of runs may be made without further addition of potassium chromate. After 5 or 6 runs, however, an additional small amount of potassium chromate, such as, for example, about 13 grams per gallon of electrolyte, is found to increase the yield of bromate.

The crystals of potassium bromate which at this stage are yellow in color, are redissolved in a suitable amount of water; for example, for the amount specified, about 50 gallons of water was used. The solution is heated and then treated with a material which adsorbs chromium such as metallic zinc or zinc dust. When zinc dust is used, the proportion of approximately 2 grams of zinc dust per 100 grams of potassium bromate crystals has been found to be effective. Materially smaller proportions of zinc apparently do not produce complete decolorization of the bromate crystals. The zinc dust should be added to the potassium bromate solution slowly and with continuous agitation in order to get good contact.

In this treatment it is believed that two reactions go on simultaneously; in the first reaction the zinc dust appears to adsorb the chromate ions in somewhat the same manner

as activated charcoal adsorbs organic material. In the second reaction the zinc appears to react with free potassium hydroxide which is present in the solution, probably forming a potassium zincate, which apparently in turn hydrolyzes to form zinc hydroxide. The zinc hydroxide then precipitates from the solution. The zinc hydroxide together with unchanged zinc dust, which carry along the chromate, are then filtered off. The filtrate is evaporated until potassium bromate crystals begin to form and the solution is then cooled until the potassium bromate has been crystallized out. The mother liquor is decanted off and may be pumped back into the original mother liquor and used as make-up liquor for another electrolysis. The potassium bromate is now obtained in the form of pure white crystals.

When potassium bromate crystals produced from an electrolysis subsequent to the first electrolysis in a series of runs, are treated according to this method, it is found that the alkalinity of the bromate solution is increased, and decolorization is in some cases not complete. However, in such cases, the alkalinity of the solution may be adjusted by the addition of a small proportion of hydrobromic acid to the bromate solution. Complete decolorization upon treatment with zinc may thus be obtained. For example, about .05% by weight of hydrobromic acid (0.75% of a dilute solution of HBr containing 6.8% HBr), based on weight of the bromate crystals, has been found to be effective in certain cases to insure complete decolorization by the zinc treatment described. The bromate solution is usually readily decolorized when the pH value of the solution is approximately 8.00. However, determinations of pH values on bromate solutions have been found somewhat unreliable. The proportion of hydrobromic acid (if any) required for any run may be determined by taking test samples of the bromate solution before the treatment with metallic zinc. Such test samples are treated with zinc and the potassium bromate crystallized according to the procedure described above. By such tests it may be readily determined whether the addition of hydrobromic acid is necessary to produce white crystals of potassium bromate, and the proportion of hydrobromic acid which is necessary to give the desired result in any plant run.

Potassium bromate crystals produced in this manner are found to contain from 99.5 to 99.9 per cent potassium bromate. Tests for zinc and potassium bromide are negative. A saturated solution of these potassium bromate crystals in water is a water-white liquor, with no trace of insoluble material. Tests for all metals except potassium are negative. Where potassium bromate of a particularly high degree of purity is re-

quired, recrystallization of the bromate crystals produced as described above, will increase the purity of the bromate crystals.

While the features herein described constitute preferred embodiments of our invention it is to be understood that the invention is not limited to these precise features, and that changes may be made therein without departing from the scope of the invention which is defined in the appended claims.

What is claimed is:

1. In the process of making a colorless alkali bromate from an alkali bromate containing a chromate, the step of removing the chromate by treating the alkali bromate solution with metallic zinc.

2. In the process of making a colorless alkali bromate from a discolored alkali bromate containing a chromate, the steps of adding hydrobromic acid to the alkali bromate solution, and then removing the chromate by treating the alkali bromate solution with metallic zinc.

3. In the manufacture of alkali bromates by the electrolysis of bromides wherein an alkali bromide solution containing a chromate as a depolarizer is electrolyzed to produce alkali bromate crystals containing chromate as an impurity, and impure bromate crystals are separated from the solution, the steps which comprise forming a solution of the impure alkali bromate crystals, adding metallic zinc to the solution to adsorb the chromate impurities and separating the zinc with the chromate from the bromate solution to obtain an alkali bromate free from chromate.

4. In the manufacture of bromate by electrolysis of bromides wherein a bromide solution containing a chromate as a depolarizer is electrolyzed to produce bromate crystals containing chromate as an impurity, the steps which comprise forming a solution of the impure bromate crystals, adding metallic zinc to the solution to adsorb the chromate impurities and separating zinc with the chromate from the bromate solution to obtain a bromate free from chromate.

5. In the manufacture of alkali bromates by electrolysis of bromides wherein a solution of an alkali bromide containing a chromate as a depolarizer is electrolyzed to produce alkali bromate containing chromate as an impurity, the step which comprises treating the alkali bromate in solution form with metallic zinc to adsorb the chromatic impurities.

6. In the manufacture of potassium bromates by the electrolysis of bromides wherein a potassium bromide solution containing a chromate as a depolarizer is electrolyzed to produce potassium bromate crystals containing chromate as an impurity, and impure potassium bromate crystals are separated from the solution, the steps which comprise forming a solution of the impure potassium bromate crystals, adding metallic zinc to the solution to adsorb the chromate impurities and separating the zinc with the chromate from the bromate solution to obtain a potassium bromate free from chromate.

7. In the manufacture of alkali bromates by electrolysis of bromides wherein an alkali bromide solution containing a chromate as a depolarizer is electrolyzed to produce alkali bromate crystals containing chromate as an impurity, the steps which comprise forming a solution of the impure alkali bromate containing a chromate as an impurity, adding hydrobromic acid, treating the alkali bromate solution with metallic zinc to adsorb the chromate impurities, and separating the zinc with the chromate from the alkali bromate solution.

8. In the manufacture of bromates by the electrolysis of bromides wherein a bromide solution containing a chromate as a depolarizer is electrolyzed to produce bromate crystals containing chromate as an impurity and the impure bromate is separated from the solution, the steps which comprise forming a solution of the impure bromate crystals, adding hydrobromic acid, treating the bromate solution with metallic zinc to adsorb the chromate impurities, and separating the zinc with the chromate from the bromate solution.

9. In the manufacture of alkali bromates by the electrolysis of bromides wherein an alkali bromide solution containing a chromate as a depolarizer is electrolyzed to produce alkali bromate crystals containing chromate as an impurity and the impure bromate is separated from the solution, the steps which comprise forming a solution of the impure alkali bromate crystals, adding hydrobromic acid, adding metallic zinc to the solution to adsorb the chromate impurities, separating the zinc with the chromate from the alkali bromate solution, and evaporating the bromate solution to obtain white alkali bromate crystals.
